RECORD MAGAZINE FOR AUTOMATIC PHONOGRAPH

David C. Rockola, Chicago, Ill., assignor to Rock-Ola Manufacturing Corporation, Chicago, Ill., a corporation of Delaware

Filed Mar. 10, 1961, Ser. No. 64,221

Term of patent 14 years

(Cl. D56—4)

FIG. 1 is a face view of a record magazine for automatic phonograph embodying my new design;

FIG. 2 is an edge view thereof with the arms continuing around the magazine as indicated by the dashed lines; and

FIG. 3 is a fragmentary perspective view thereof on a reduced scale.

I claim:

The ornamental design for a record magazine for automatic phonograph, substantially as shown and described.
